[57] CLAIM

The ornamental design for a bottom surface of a shoe
outsole, as shown and described.

DESCRIPTION

FIG. 1 is a perspective view of a bottom surface of a shoe
outsole showing my new design;

FIG. 2 is a rear elevational view of the bottom surface of a
shoe outsole shown in FIG. 1;

FIG. 3 is a front elevational view of the bottom surface of
a shoe outsole shown in FIG. 1;

FIG. 4 is a side elevational view of one side of the bottom
surface of a shoe outsole shown in FIG. 1;

FIG. 5 is a side elevational view of the other side of the
bottom surface of a shoe outsole shown in FIG. 1;

FIG. 6 is a plan view of the bottom surface of a shoe outsole
shown in FIG. 1;

FIG. 7 is a cross-sectional profile view of the bottom surface
of a shoe outsole taken along line 7—7 of FIG. 6;

FIG. 8 is a cross-sectional profile view of the bottom surface
of a shoe outsole taken along line 8—8 of FIG. 6;

FIG. 9 is a cross-sectional profile view of the bottom surface
of a shoe outsole taken along line 9—9 of FIG. 6; and

FIG. 10 is a cross-sectional profile view of the bottom surface
of a shoe outsole taken along line 10—10 of FIG. 6.

The broken line showing of the remainder of the shoe is for
illustrative purposes and forms no part of the claimed
design.
